UNITED STATES PATENT OFFICE.

EDWIN K. O'BRIEN, OF ALEXANDRIA, VIRGINIA.

HYDRAULIC-RAM DREDGE.

1,170,930.

Specification of Letters Patent. Patented Feb. 8, 1916.

Application filed November 4, 1914. Serial No. 870,219.

To all whom it may concern:

Be it known that I, EDWIN K. O'BRIEN, a citizen of the United States, residing at Alexandria, in the county of Alexandria and State of Virginia, have invented certain new and useful Improvements in Hydraulic-Ram Dredges, of which the following is a specification.

This invention relates to hydraulic ram dredges, and it includes in combination a hydraulic ram and hydraulic excavating appliances, the parts having preferably special construction and arrangement with regard to each other, and the whole being intended particularly for use where a large amount of water is available which has only a small head or fall. Such conditions arise in connection with marsh lands situated near tide water, where it is practicable to provide, by the construction of dikes of appropriate position and extent, a receiving reservoir for the inflow of the tide water by which the ram and its dredging members are operated, and by which the stirred up silt or soil with the water carrying it may be sucked up and impelled through suitable lift pipes to the places of deposit desired. After a time during the relatively high period of the tide, the reservoir fills up, and as the tide falls the water in the reservoir becomes higher than that on the outside, and the water then flows from the reservoir in a reversed direction through the ram.

It is an object of this invention, consequently, to produce apparatus of the character and for the purpose set forth, wherein the ram will be operated, and the dredging and soil-lifting operations carried on, whichever direction is taken by the flowing water through the ram, as the head sufficient therefor is attained.

The construction of the various parts of this invention, and the arrangement of those parts, are illustrated in the accompanying drawings, of which—

Figure 1 represents a vertical section of this invention in operative position, and showing the intake, discharge and lift pipes connected with it. Fig. 2 is a vertical section of this invention taken on a plane at right angles with the plane of the section in Fig. 1. Fig. 3 is a plan view of the valve, somewhat enlarged. Fig. 4 is a side view of the rotary valve, the scale of drawing being the same as in Fig. 3. Fig. 5 is a vertical section lengthwise of the clear water

intake, and the concentric soil and water intake, and illustrates, on a somewhat enlarged scale of drawing, the dredging devices and the driving turbine.

Throughout the drawings and description, the same letter refers to the same part.

Considering the drawings, the dike or embankment A being erected, the frame a is set up usually on the tide water side of the dike, and by means of hangers B the ram b is supported upon the frame. The ram is provided with the discharge pipe C, in this description termed the clear water discharge pipe to distinguish it from the soil and water discharge or lift pipes. The ram has a clear water intake D, that is constructed ordinarily in practice with an elbow d having a movably threaded or like connection with a turning bowl or hollow head E. Thus, the outer end of the intake D may rise or fall, or the intake may be swung around horizontally.

This invention is also provided with the discharge pipes F and f for soil and water, and opening into the ram b at right angles with the discharge pipe C. The discharge or lift pipes F and f, are connected by the inclined pipes G and g with the upper and stationary portion H of the soil and water intake pipe. The inclined pipes G and g are termed in this application, the suction pipes, as through them the soil and water are sucked up into the pipes F and f. By means of the sleeve connection h, the vertical arm of the elbow K of the soil and water intake k, may turn on its axis. That is to say, if the hollow head or bowl bottom E of the ram b is turned, the vertical arm of the elbow K will turn on its axis, as it rises in the center of the bowl E. It will be here noted in Figs. 1 and 5, that the clear water intake D carries the soil and water intake k axially within it, as this invention is customarily constructed.

At the outer end of the intake D there is arranged a revoluble sleeve L, and at the outer end of the sleeve L there is secured the stirrer M. The sleeve is revolved in the bearing m by the turbine N on the flow of the water in the intake D. It may be stated here, that the soil or silt intended to be dislodged and carried by the water in suspension, is very easily stirred up. In its finely divided state it requires but little dredging to displace it and mix it with the water around it.

The rotary valve of the ram is marked O, and it has the turbine buckets P and Q, one above the other as best shown in Fig. 4. The buckets are designed to revolve the 5 valve, whatever may be the direction of the water flowing through the ram. The remaining parts of this invention are best described in connection with the explanation of its mode of operation.

10 In the operation of this invention, let it be assumed that the buckets of the valve have taken the positions indicated by the broken lines in Fig. 2. There will be noted the two extensions or recesses R and r of 15 the casing of the ram b, that enable the water flowing in either direction to pass the buckets when they are in the positions indicated. The valve will be revolved, and in due course the cylindrical wall of the 20 valve will close the recesses R and r. The water cannot now reach the discharge pipe C which opens above the valve, but, the water finds an outlet by way of the pipe f after passing through the bucket Q. In 25 other words, the flow of the water in the clear water intake D is never stopped. It either flows outwardly by way of the discharge pipe C, or, by way of the soil and water discharge pipe f. There is now 30 started an outwardly moving column of water in the pipe f, driven with some force by the momentum of the water flowing in through the intake D. That intake may be, and usually is, of some length. The valve 35 O is still turning under the action of the flowing water, and the cylindrical wall of the valve soon closes the adjacent opening or mouth of the pipe f. The moving water in the pipe f sucks in a portion of soil and 40 water through the suction pipe g, and that portion of soil and water is impelled through the pipe f when the flow is again started therein. The lift or soil and water pipes are led to that area whereon it is 45 desired to deposit the soil carried by the water. The stirrer M is being constantly rotated and keeps the water near it charged with soil. If for any reason the stirrer should become obstructed, the water will 50 continue to enter both the intake D and the soil intake k, and, the inflow of the water alone is ordinarily capable of stirring up the easily floated soil to a very large extent. Up to this point in this explanation of the 55 operation, it has been supposed that the water has been flowing into the intake D, by reason of the high tide on the left or outside of the embankment A, the high water mark being indicated in Fig. 1. Let 60 it be now supposed that the tide has receded and the low water mark, also indicated in Fig. 1 has been reached. The reservoir or sink on the right of the embankment A will have been filled during the tidal operation, 65 and the water from the right of the embank-

ment A will now flow through the ram b and outwardly through the intake D. The flow of water is constant as before, and the valve is revolved. The water flows into the ram by way of the clear water discharge pipe C, and is diverted periodically by the valve buckets P into the soil and water discharge pipe F, and a flow started outwardly in that pipe by the momentum of the inflowing water in the pipe C. When the cylindrical portion of the wall of the valve closes the opening of the pipe F adjacent to the valve, the flow in the pipe F sucks up a portion of the soil and water through the intake k and the suction pipe G. That is to say, when the water flows upwardly through the ram as the parts are illustrated in the drawings, the soil and water discharge pipe f is in service. But, when the water flows downwardly through the ram, the pipe F is engaged. By the use of this invention, both the rise and fall of the tide may be used to a greater or less extent.

Having now described this invention, and explained the mode of its operation, what I claim is:

1. In a hydraulic ram dredge, the combination with a ram having a clear water intake, a valve, and a soil and water intake, of a discharge pipe from the said ram, and a suction pipe leading from the said soil and water intake and opening into the said discharge pipe beyond the said valve.

2. In a hydraulic ram dredge, the combination with a ram having a clear water intake, a valve, a soil and water intake, a discharge pipe for clear water, a discharge pipe for soil and water, the said valve being arranged to control the said discharge pipes, and a suction pipe leading from the said soil and water intake and opening into the said discharge pipe for soil and water beyond the said valve.

3. In a hydraulic ram dredge, the combination with a ram having a movable clear water intake, a valve, a movable soil and water intake, a discharge pipe for clear water, a discharge pipe for soil and water, the said valve being arranged to control the said discharge pipes, and a suction pipe connected with the said soil and water intake and opening into the said soil and water discharge pipe beyond the said valve.

4. In a hydraulic ram dredge, the combination with a ram having a movable clear water intake, a valve, a movable soil and water intake arranged lengthwise within the said clear water intake, a discharge pipe from the ram, and a suction pipe leading from the said soil and water intake and opening into the said discharge pipe beyond the said valve.

5. In a hydraulic ram dredge, the combination with a ram having a clear water intake, a valve, a soil and water intake ar-

ranged lengthwise within the said clear water intake, a discharge pipe for clear water, a discharge pipe for soil and water, the said valve being arranged to control the 5 said discharge pipes, and a suction pipe connected with the said soil and water intake and opening into the said soil and water discharge pipe beyond the said valve.

6. In a hydraulic ram dredge, the combination with a ram having a movable clear water intake, a valve, a movable soil and water intake, movable means arranged at the mouth of the said soil and water intake and constructed to stir up the soil, means for 15 operating the said stirring means, the said ram having a discharge pipe, the said valve being arranged to control the said discharge pipe, and a suction pipe leading from the 20 said soil and water intake and opening into the said discharge pipe beyond the said valve.

7. In a hydraulic ram dredge, the combination with a ram having a soil and water intake, a rotary valve, a discharge pipe opening adjacent to the valve and controlled by the valve, a suction pipe connecting the said discharge pipe and the said soil and water intake, a clear water discharge pipe connected with the said ram, and a water intake 30 connected with the ram below the said valve.

8. In a hydraulic ram dredge, the combination with a ram having a rotary valve, of a discharge pipe opening adjacent to the valve and controlled by the valve, a soil and water suction pipe connected with the said discharge pipe, a clear water intake connected with the ram below the valve, and a clear water discharge pipe.

9. In a hydraulic ram dredge, the combination with a ram having a rotary valve, of a discharge pipe opening adjacent to the valve, a clear water intake connected with the ram below the said valve, a clear water discharge pipe, 40 a soil and water intake arranged lengthwise within the said clear water intake, and a suction pipe connecting the said soil and water intake with the said discharge pipe mentioned as opening adjacent to the valve.

10. In a hydraulic ram dredge, the combination with a ram having a soil and water intake, of a rotary valve having buckets arranged one over another whereby water flowing in either direction will revolve the valve, discharge pipes opening adjacent to the said 55 valve one opening at a higher point than another, the buckets of the valve being positioned to register with the said openings of the discharge pipes, soil and water suction pipes connected with the said discharge 60 pipes, a clear water intake opening below the valve, a clear water discharge pipe opening above the said valve, and the wall of the ram having recesses for the passage of water past the valve to the said discharge pipe 65 above the valve when the valve is in a predetermined position.

11. In a hydraulic ram, the combination with an intake, of a discharge pipe, a lift discharge pipe, a valve, the mouths of all 70 the said discharge pipes being arranged near and controlled by the said valve, the said valve being constructed to periodically cut off the passage of the water into the said pipes, and the said valve being provided 75 with means for actuating it by the flow of water in different directions through the ram.

12. In a hydraulic ram, the combination with an intake, of a discharge pipe, a lift 80 discharge pipe, a rotary valve, the mouths of all the said discharge pipes being arranged near and controlled by the said valve, the said valve being constructed to periodically cut off the passage of the water into the 85 said pipes, the said valve being provided with buckets whereby the flow of water in either direction through the ram revolves the valve, and the ram having a portion extending below the said valve and connected 90 with the said intake.

In testimony whereof I affix my signature in presence of two witnesses.

EDWIN K. O'BRIEN.
